(57) **CLAIM**

We claim the ornamental design for a telescoping weather resistant box, as shown and described.

DESCRIPTION

FIG. 1 is a bottom end view of a telescoping weather resistant box in its extended stage showing my new design; FIG. 2 is a front view thereof;

FIG. 3 is a left side view of the telescoping weather resistant box in its extended stage;

FIG. 4 is a right side view of the telescoping weather resistant box in its extended stage;

FIG. 5 is a rear view of the telescoping weather resistant box; and,

FIG. 6 is a top end view of the telescoping weather resistant box in its extended stage.
